Attorney

UNITED STATES PATENT OFFICE.

ADOLPH THIELE, OF ESPANOLA, WASHINGTON.

SUPPORT.

Application filed December 12, 1924. Serial No. 755,404.

My present invention relates to improvements in supports designed especially for use as a supporting frame for children's cribs, bassinets, baskets for holding clothes in the laundry, and for other similar articles capable of being suspended according to my invention.

The support is of the extensible, knock-down foldable type adapting it readily for use with various lengths of receptacles and providing for a compact arrangement of parts for packing, storing and shipping the device. The primary object of the invention is the provision of a device of this character which is comparatively inexpensive in cost of production, simple in construction in order that it may with facility be assembled for use, or its parts dissociated for shipping or storing, durable, and insuring a stable and convenient supporting frame for articles suspended therein.

These objects are accomplished by means of certain novel combinations and arrangements of frame parts with joint parts as will hereinafter be more fully set forth and claimed.

In the accompanying drawings I have illustrated one complete example of the physical embodiment of my invention where-in the parts are combined and arranged according to the best mode I have thus far devised for the practical application of the principles of my invention.

Figure 1 is a perspective view of the device of my invention shown in use as a support for a basket or similar receptacle.

Figure 2 is a perspective view showing one of the joints at the base of a post.

Figure 3 is a perspective view of one of the post-bushings.

Figure 4 is a perspective view of one of the base-bushings.

Figure 5 is a perspective view of one section of the device, folded in compact form for storing or shipping.

The parts constituting the supporting frame are preferably composed of suitable lengths of pipes or rods of the desired or required dimensions, and the base of the frame includes a pair of spaced cross bars as 1 and 2 each provided with a pair of legs as 3 and 4 bent downwardly at right angles from the cross bars, and provided with feet 5.

These cross bars are connected by a pair of telescoping longitudinally disposed bars 6 and 7 which are secured together by a set

screw 8 in the former section and adapted to frictionally engage the latter section as usual.

The cross bars and longitudinal bars provide a rigid frame structure for the upright posts 9 and 10 which rise therefrom, and the posts, at their upper ends are provided with suspending hooks 11 between which a basket 12 or other receptacle may be suspended by utilizing the handles 13, at the respective ends of the basket, to engage these hooks.

At the lower end of the post 10 a bushing 14 is threaded and as seen in Fig. 3 the bushing is fashioned with a wedge shaped flange 15 extending laterally therefrom and provided with a transverse groove 16 in the upper face of the flange, said groove being adapted to be engaged by a fastening ring 17.

The post 9 is also provided with a duplicate bushing 18 having a wedge flange 19, and the respective bushings 14 and 18 have integral perforated ears 20 and 21. A ring 22 similar to ring 17 is used to secure the post 9 to the bar 1.

On the respective cross bars 1 and 2 are provided sleeves 23 and 24, each of which has a set screw 25 adapted to engage a hole 26 in the cross bar and secure the sleeve in position at the center thereof. These sleeves are fashioned with pairs of integral perforated ears 27 and 28 of which the pairs 27 are adapted to receive the lugs 20 and 21 and the respective ears and lugs are secured together by screws or bolts as usual.

On the outer end of the telescoping bar 6 is secured a bushing 28 of the type shown in Fig. 3 and fashioned with a wedge flange 29 and a perforated lug 30 the latter for co-action with the ears 26. A complementary bushing 31 is secured at the outer end of the telescoping section 7 having a wedge flange 32 and perforated lug 33, the latter also co-acting with a pair of perforated ears 26 on sleeve 24.

The fastening ring 34 similar to ring 22 is employed to join the parts at the joint of post 9 and cross bar 1.

Thus it will be apparent that the parts are standardized to utilize a pair of post bushings, a pair of base bushings on the ends of the telescoping members, and a pair of sleeves on the cross bars, said bushings and sleeves respectively being of duplicate construction. The posts 9 and 10, as well as

the fastening rings 17 and 22 are also of duplicate construction. This standardization of parts renders the assembly of parts a simple matter, without the necessity for use of tools, and without the necessity for skilled labor.

When the fastening screws or bolts and the slip or friction rings are in place the structure is given the required rigidity and strength for utilization as a supporting frame, and the length of the frame may be varied within limits by adjusting the telescoping longitudinal bars 6 and 7 and securing them together in adjusted position by 15 turning tight the bolt or hand screw 8.

The rigid frame may readily be disassociated by first withdrawing the fastening rings from their grooved flanges, then removing the bolts or screws from the perforated ears and lugs and loosening the clamp screws 8 and 25, after which the frame may be detached into two sections by withdrawing bar 7 from bar 6, and the separated sections may be folded as indicated in Figure 25 5. In this compact arrangement of the parts that they may be stored away when not in use, or packed for shipping.

Having thus fully described my invention, what I claim as new and desire to secure by Letters Patent is—

1. A supporting frame comprising a pair of cross bars, a longitudinal connecting bar, and upright posts supported from said cross bars, a joint-sleeve on each cross bar, complementary joint bushings on adjoining ends of said posts and connecting bar, each joint sleeve having pivotally connected to it one of said connecting-bar bushings and one of 35 said post bushings and means at each end of the longitudinal bar for releasably locking the longitudinal bar, one of said posts,

and one of said cross bars all at substantially right angles to each other.

2. A supporting frame comprising a pair of cross bars with supporting feet, a telescoping connecting bar, and upright posts having suspending means thereon, a pair of 45 adjustable joint sleeves on the cross bars and securing means therefor, a pair of joint-bushings on the posts and a pair of joint-bushings on the connecting bar, and means for releasably locking together each sleeve with a pair of joint-bushings.

3. The combination with a pair of cross bars each having a sleeve thereon and angularly disposed perforated ears on each sleeve, of a connecting bar having a bushing end and a perforated ear and wedge-flange on each bushing, a pair of posts each having a bushing thereon and a perforated ear and wedge-flange on each bushing, bolts for securing the ears of the respective bushings with the ears of the sleeve, and a slip ring encircling each sleeve for engaging the adjacent wedge-flanges.

4. The combination in a frame support with a cross bar, a sleeve on the bar and a set screw in the sleeve, and pairs of angularly disposed ears on said sleeve, of a connecting bar having a bushing at one end, 65 said bushing provided with an ear for coaction with one of said pairs of ears, a post having a bushing thereon, said bushing provided with an ear for coaction with the other pair of ears, wedge shaped flanges on 70 each bushing and a slip ring encircling the sleeve to engage said flanges, and bolts for securing the ears of the respective bushings with the ears of the sleeve.

In testimony whereof I affix my signature.

ADOLPH THIELE.
